L. U. CORNELIUS.

ADVERTISING APPARATUS.

APPLICATION FILED OCT. 2, 1908.

923,335.

Patented June 1, 1909.

UNITED STATES PATENT OFFICE.

LESLIE U. CORNELIUS, OF ROCKY HILL STATION, KENTUCKY.

ADVERTISING APPARATUS.

No. 923,335.

Specification of Letters Patent.

Patented June 1, 1909.

Application filed October 2, 1908. Serial No. 455,860.

To all whom it may concern:

Be it known that I, LESLIE U. CORNELIUS, a citizen of the United States, residing at Rocky Hill Station, in the county of Edmonson and State of Kentucky, have invented a new and useful Advertising Apparatus, of which the following is a specification.

This invention relates to advertising boards.

10 The object of the invention is to provide an article of this character that shall be simple of construction, efficient and durable in use, cheap to manufacture, and in which the advertising matter may readily be positioned and removed, as required, be positively held in place against danger of accidental displacing, as from wind or rain, and in which such matter shall be displayed in the most advantageous manner. Furthermore, to 15 adapt the article as a means for informing travelers of the distance in miles from a given board to a town, the business interests of which are displayed by the board.

With the above and other objects in view, 20 as will appear as the nature of the invention is better understood, the same consists in the novel construction and combination of parts of an advertising board, as will be herein-after fully described and claimed.

30 In the accompanying drawings forming a part of this specification, and in which like characters of reference indicate corresponding parts:—Figure 1 is a view in perspective of the board with the front panel or frame thereof partly lifted to display the keepers for holding the advertising matter in position. Fig. 2 is a vertical transverse sectional view through the board with the frame in normal or closed position.

40 The article comprises a back or support 1, and a gridded frame designated generally 2. The back 1 may be made of any suitable material, such as boards, or of boards covered with sheet metal, such as galvanized iron. This back is supported by uprights 3, which are sunk an appropriate distance in the ground adjacent to a highway and are stayed by inclined braces 4.

It is designed that the face of the back 50 shall contain advertisements of various business interests, and these advertisements will generally be printed or otherwise displayed, either upon water-proof paper or upon metal, as may be preferred. In order to exhibit the 55 advertising matter to the best advantage, the front of the support 1 is divided into a

series of spaces by longitudinal keepers 5, 6, and 7 and vertical keepers 8, 9, and 10, the keepers being held away from the support a sufficient distance to permit insertion of the 60 surfaces bearing the advertising matter by the spacers 11, which may be of any suitable material, the keepers and spacers being held assembled with the support by nails, screws, or other suitable form of fastening device 12. 65

As herein shown, the keepers 5, 6, 7 and 8 define four spaces to receive the panels 13 bearing the advertising matter, these panels being inserted through the two ends of the support. 70

The keepers 7, 9 and 10 define a single space in which is arranged a panel 14, upon which is displayed the distance in miles to the town or city, the advertisements of whose merchants is carried by the support. 75 The panel 14 is inserted through the top edge of the support, and in order to permit this, the frame 2 carries at its upper edge a batten 15, the rear edge of which is connected with the back of the support by hinges 16, and so this will allow the frame to be turned backwardly a sufficient distance to move it out of any interfering position with regard to the keepers 9 and 10.

The frame may be constructed from any 80 suitable material, such as wood, a combination of wood and sheet metal, or wholly of metal, and comprises four longitudinal strips 17, 18, 19, and 20, three transverse strips 21, 22 and 23, two end battens 24 and 25, and the 85 top batten 15 above referred to, the battens 24 and 25 being of a width completely to cover the ends of the support, and thus prevent the panels bearing the advertising matter from becoming accidentally detached 90 from the support. The strip or frame member 17 is inset from the lower ends of the battens 24 and 25 in order to allow the strip 17 to overlie a batten 26 secured to the lower edge of the support, the ends 27 of the battens 24 and 25 that project beyond the strip 100 17 being designed to inclose the ends of the batten 26, and thus reinforce the frame and also to prevent any end shaking, as from wind pressure. 105

The strips 17, 18, 19, 21, 22, and 23 define four openings that are of a size corresponding to the panel receiving openings, and the said strips serve effectually to conceal the keepers of the support, while the strips 19, 20, 21, and 23 define an opening of a size approximating that of the panel 14. In order to 110

retain the frame in temporary locked position with relation to the support, any suitable means may be employed, that herein shown consisting of a pair of spring catches 5 28 that are secured to the batten 26, and are adapted to spring over the front edge of the batten 17.

While there has been shown but four spaces for receiving advertising matter, it is 10 to be understood that the invention is not to be limited to this number, as many as may be desired may be provided, and still be within the scope of the invention.

The object for having the panels bearing 15 the advertising matter removable, is to permit of their being changed, as the purpose of the invention is to make the device a paying one, that is by charging the advertisers so much for a month or a half month for the 20 privilege. It is intended that the board shall be set at a distance of from fifteen to thirty-five feet from the road and that the signs shall be painted, printed from lithographed plates or from wood type in large, clear, 25 bold letters, so that they may be easily read by one passing.

The feature of constituting the device a distance indicator will be appreciated by persons traveling over roads employing this 30 particular form of advertising board.

It will be observed from an inspection of 35 the drawings that the strips 17, 18, and 19 are each of a greater width than the keeper which it covers when the frame is in position against the back or support of the sign board and the keepers are in this manner not only concealed from view but protected and a sign having a neat appearance is produced.

I claim:—

1. An advertising board comprising a 40 back, keepers secured to the face of the back and spaced therefrom to receive surfaces bearing advertising matter, and a frame hinged to the back and comprising strips which, when the frame is in position against 45 the back coincide with the keepers and cover the same.

2. An advertising board comprising a back or support, keepers secured to the face thereof and spaced therefrom to provide 50 guides to receive panels bearing advertising matter, a frame arranged in front of the back and divided into openings approximating the size of the advertising panels, a batten carried by the upper edge of the frame and 55 projecting over the upper edge of the back, hinges connecting the rear edge of the batten and the rear face of the back, end battens carried by the frame and inclosing the ends 60 of the back to prevent lateral displacement of the advertising panels, the lower ends of the latter battens being projected beyond the lower edge of the frame, a batten secured to the lower edge of the back and arranged between the extended portions of the frame 65 battens to prevent end shake of the frame, and means for holding the frame and back detachably connected.

In testimony that I claim the foregoing as my own, I have hereto affixed my signature 70 in the presence of two witnesses.

LESLIE U. CORNELIUS.
